DESIGN FOR A COMBINED COMPACT AND SCENT SPRAY

Richard Bugbee, Milner, British Columbia,
Canada

Application December 12, 1947, Serial No. 143,109

Term of patent 7 years

(Cl. D86—10)

To all whom it may concern:

Be it known that I, Richard Bugbee, a subject of the King of Great Britain and a resident of Milner, in the Province of British Columbia, Canada, have invented a new, original, and ornamental Design for a Combined Compact and Scent Spray, of which the following is a specification, reference being had to the accompanying drawing, forming part thereof, wherein the figure is a perspective view of a combined compact and scent spray showing my new design. The reverse side of the combined compact and scent spray is of plain design.

I claim:

The ornamental design for a combined compact and scent spray, as shown and described.

RICHARD BUGBEE.
